ATTORNEY

UNITED STATES PATENT OFFICE

JOHN RATTANZI, OF BROOKLYN, NEW YORK

CLAMP AND SHOE LAST VISE

Application filed August 17, 1929. Serial No. 386,721.

This invention relates to shoe vises or clamps and more particularly to a table or bench vise of the type shown and described in my co-pending application Serial No. 362,112, filed May 10th, 1929.

One of the objects of my invention is to provide a shoe vise particularly adapted for shoe lasts of various types and sizes to facilitate the hand sewing operations.

Another object of my invention is to provide a vise and bench clamp including provision for positioning a detachable shoe last whereby the shoe and particularly the heel portion may be firmly held in position to enable the operator to perform the hand sewing operations on the sole and shoe upper.

A further object of my invention is to construct a combined vise and clamp which will be simple, easily manufactured at a comparatively low cost, efficient and practical, strong, durable and capable of use on any type of work bench either in the factory or individual shop.

To enable others skilled in the art to more fully comprehend the underlying features of my invention, reference is had to the accompanying drawings forming a part of this specification in which

Fig. 1 is a front view.

Fig. 2 is an end view.

Fig. 3 is a top plan.

Fig. 4 is a detail taken on the line 4—4 of Fig. 1.

Referring now to the drawings wherein like reference characters designate corresponding parts throughout the several views, 5 designates an annular base or support which is preferably integral with an upwardly tapered post or standard 6 having a central bore or opening to receive the lower end 7 of a removable, freely rotatable rod 8. The post or standard is tapped to receive a wing screw 9 for locking the rod.

On the rod 8 a yoke shaped casting or frame 9a having a central hollow boss 10 is positioned, said boss being tapped to receive a threaded wing screw 11 for locking said casting or frame to the rod. The vertical arm 12 of the casting or frame is provided

en ed surface 13 on its inner face for directly engaging the heel portion of a shoe which is positioned on the shoe last or form 14.

The shoe last or form is provided with an opening to receive the smooth end 15 of a feed screw 16. The feed screw is mounted in a transverse, internally threaded boss 17 on the upper end of the opposite arm 18 of the frame or casting. On the end of the feed screw, I provide a hand wheel or handle 19 whereby the screw may be rotated to advance the shoe last or form toward the serrated surface of the opposite arm, thus clamping the shoe in position to facilitate work thereon.

From this construction, it will be seen that the shoe last or form may be set at any desired angle relative to the frame or casting and either locked or unlocked quickly by the proper rotation of the feed screw. Since the shoe lasts or forms are standardized, the device is adapted for use on either men's, women's or children's shoes.

While I have shown and described my invention with some degree of particularity, it will be realized that other modifications and changes may be resorted to under special conditions. I therefore do not wish to be limited and restricted to the exact details shown and described but reserve the right to make such changes and modifications as may fairly fall within the scope of the subject matter now being claimed.

Having shown and described my invention, what I claim as new and desire to secure by Letters Patent is:

1. A device of the class described comprising a base having a standard, a rod adapted to be adjusted within the standard, around and along a vertical axis, means for locking said rod in said standard, a yoke shaped frame on the upper end of the rod, means for locking said frame to the rod, one arm of said frame having a substantially vertical roughened surface on its inner face adapted to engage the heel portion of a shoe, a feed screw engaged in a tapped, horizontally disposed hole on the upper end of the opposite arm of said frame, a shoe last on one end of the feed screw, and a hand wheel on the opposite end of said screw for advancing

or retarding said last, relative to the roughened surface of said arm.

2. A clamp and shoe last vise, comprising a base having a standard, a rod adapted to be adjusted within the standard around and along a vertical axis, means for locking said rod in said standard, a yoke shaped frame on the upper end of the rod, means for locking said frame to said rod, one arm of said frame having a substantially vertically disposed roughened surface on its inner face, adapted to engage the heel portion of a shoe, a feed screw engaged in a tapped, horizontally disposed hole on the upper end of the opposite arm of said frame, a shoe last rotatably and removably mounted on one end of the feed screw and substantially radially extending therefrom, and a hand wheel on the opposite end of said screw for advancing and withdrawing said last, relative to the roughened surface of said arm.
3. In a clamp and shoe last vise, a standard, a yoke shaped frame mounted on said standard and adapted to be adjusted vertically, as well as angularly, in a horizontal plane, in relation to said standard, a pivot screw carried by one arm of said frame and horizontally adjustable towards and away from the opposite arm of said frame, and a last rotatably and removably supported at its heel portion by the cylindrical end of said screw, and a serrated, substantially vertical surface on said opposite arm registering with and facing towards the heel portion of said last, said last being adapted to be clamped by said screw against said serrated surface in a position of preferred angular adjustment in a vertical plane.

In testimony whereof I affix my signature.

JOHN RATTAZZI.
